ATTORNEY

UNITED STATES PATENT OFFICE.

ANTON REZNICEK, OF JERSEY CITY, NEW JERSEY.

SUSPENDER-STRAP HOLDER.

1,261,960.

Specification of Letters Patent.

Patented Apr. 9, 1918.

Application filed June 22, 1916. Serial No. 105,104.

To all whom it may concern:

Be it known that I, ANTON REZNICEK, a citizen of the United States, and resident of Jersey City, in the county of Hudson, State 5 of New Jersey, have invented certain new and useful Improvements in Suspender-Strap Holders, of which the following is a specification.

The present invention relates to improvements in suspender strap holders, and has for an object to provide such a device which will form a secure holding means for the suspender strap, which will be unbreakable, incapable of being torn, and easy to open 15 and close. A further object is to provide non-yielding passages through the clasp so that free movement of the connecting strap is permitted.

With these and other objects in view, my 20 invention is shown in the accompanying drawings and will be hereinafter more fully described with reference thereto, and finally pointed out in the claim.

In the accompanying drawings,

25 Figure 1 is a front view of a suspender end showing my invention embodied therein,

Fig. 2 is a vertical sectional view thereof,

Fig. 3 is a plan view of the metal reinforcing member employed, and one of the 30 leather cover pieces,

Fig. 4 is a front view of a slightly modified form of construction, and

Fig. 5 is a vertical sectional view thereof.

Similar reference characters indicate corresponding parts throughout the several figures of the drawings.

Referring to the drawings, and more particularly to Figs. 1 to 3 thereof, my improved invention consists in the clasp which is attached to the suspender strap 10 by the connecting member 11, and supports the button engaging strap 12, and comprises a metallic former or inlay and reinforcing member 13, preferably formed of non-yielding 40 metal and covered with leather or other suitable cover pieces 14 and 15, larger than the metal piece, and stitched together at 16. A pair of openings 17 and 18 are provided in one end of the metal piece, and the end is 45 inserted in the connecting member 11 and bent upon itself so that the openings register, one portion 19 of a snap fastener being secured in the said openings. The other portion 20 of the snap fastener is secured

at the other end of the metallic former 55 through an opening 21 therein.

The former is bent in such manner that the two portions of the snap fasteners are in co-operative alinement, and the loop thus formed is indented as at 22, so that the 60 lower end conforms to the rounded contour of the strap 12. In this way a passage having rigid walls is provided, and the pull on the suspender will not bind the strap in the clasp, so that free movement is permitted. 65 As there is no torsional strain on the snap fastener, this will retain its holding properties indefinitely, and the rigidity of the clasp prevents the pulling of the enlarged end of the strap 12 through the same. 70 There are practically no points of wear, so that there is no danger of the clasp breaking at an inopportune time. The clasp may be opened and closed as many times as desired, and will always retain its shape. 75

The clasp may be made of brass, or any other suitable material which is unbreakable.

In Figs. 4 and 5 I have illustrated a slightly modified form of construction, in 80 which the leather covering pieces 23 and 24 are cemented or glued to the metallic reinforcing member, the cover piece 24 only extending partially over the reinforcing strap, so that the metallic connecting member 85 11 contacts directly with the metal reinforcing strap, providing a metal against metal connection, in which there is practically no deterioration due to wearing of the parts. The thickness of the cover piece 90 24 provides a free non-yielding space for the connecting member 11, so that free movement thereof is permitted.

I have illustrated preferred and satisfactory forms of my invention, but it is obvious that changes may be made therein within the spirit and scope thereof, as defined in the appended claim. 95

I claim:

In combination with a suspender web or 100 strap, a connecting loop therefor through which the suspender web or strap passes, and a suspender end of a suspender cast-off comprising an elongated strap composed of a thin flexible sheet metal layer having an 105 exterior surface coating of leather, said strap having one end turned back on itself and fastened to the body portion of the

member to form a loop connecting with the connecting loop on the suspender web or strap, and having a snap fastening device coöperating with a snap fastener on the free 5 end of the body portion, said snap fastening device coöperating to form the body portion into a loop for holding the suspender end.

Copies of this patent may be obtained for five cents each, by addressing the "Commissioner of Patents, Washington, D. C."

In testimony that I claim the foregoing as my invention, I have signed my name in 10 presence of two subscribing witnesses.

ANTON REZNICEK.
